METHOD OF FINISHING GEARS

Walter S. Praeg, Detroit, Mich., assignor to National Broach and Machine Company, Detroit, Mich., a corporation of Michigan

Original application November 8, 1948, Serial No. 58,895. Divided and this application May 29, 1950, Serial No. 165,079

6 Claims. (Cl. 51—287)

1
The present invention relates to a method of finishing gears and more particularly, to finishing gears by rotating them in mesh under pressure at crossed axes with a gear-like lapping tool.

The present application is a division of my prior copending application, Serial No. 58,895 filed November 8, 1948, in which claims are directed to the machine for finishing gears.

It is an object of the present invention to finish gears by a method characterized by the fact that it automatically results in the removal of a predetermined amount of stock from the work gear independent of the actual size of the work gear prior to the finishing operation.

More specifically, it is an object of the present invention to provide a method of finishing gears in which a gear is meshed at crossed axes with a gear-like finishing tool, preferably a lapping tool, with the common normal to the axis of the gear and tool spaced outwardly from the adjacent end of the gear under light pressure contact, thereafter rigidly maintaining the axis in spaced relationship, rotating the gear and tool in mesh, and effecting a relative traverse between the gear and tool in a direction effective to distribute the finishing action of the tool from end to end of the gear teeth.

Other objects and features of the invention will become apparent as the description proceeds, especially when taken in conjunction with the accompanying drawings, wherein:

Figure 1 is a front elevation of a gear lapping machine constructed in accordance with the present invention.

Figure 2 is a plan view, partly in section, of the movable gear supporting table.

Figure 3 is a section on the line 3—3 of Figure 2.

Figure 4 is a section on the line 4—4 of Figure 3.

Figure 5 is a section on the line 5—5 of Figure 2.

Figure 6 is an enlarged sectional view of parts shown in Figure 3.

Figure 7 is an enlarged diagrammatic view of a rotary cam.

Figure 8 is a fragmentary section showing a detail of the machine.

The herein disclosed method may be carried out by widely different mechanisms but a machine for carrying out the herein disclosed method is illustrated in the drawings.

Referring first to Figure 1, the gear lapping machine comprises a pedestal 10 provided with a forwardly projecting overhanging portion 11,

5 to the underside of which is mounted a lap supporting head 12. The lap supporting head 12 is mounted for angular adjustment about a vertical axis to permit variation in the crossed axes angle between the gear and lap. A motor (not shown) is mounted in the portion 11 of the machine and is adapted to rotate the lap supporting spindle 13 through suitable mechanism.

10 Mounted for vertical adjustment on ways provided at the front of the pedestal 10 is a knee 15 having horizontal ways extending transversely of the machine. Mounted on these ways for back and forth reciprocation is a carriage 20. Located within the base of the machine is a motor which includes drive means for effecting 15 relatively slow reciprocation of the carriage 20 and control means for the motor are provided including suitable switches having switch actuators 22 and 24 adapted to be engaged by adjustable dogs 26 and 28.

20 Mounted on the carriage 20 is a rocking sub-table 30, a suitable trunnion connection indicated at 32 being provided between the carriage 20 and the sub-table 30. The stationary base of 25 the machine includes an adjustable cam indicated generally at 34 and a cam follower 35 is mounted on a rocking table. Releasable clamping means 36 and 38 are provided for locking the sub-table 30 in intermediate position when it is not desired to employ the cam for rocking the platform. The upper surface of the table terminates in a circular plate 40 provided with circular T-slots (not shown) on which is mounted an angularly adjustable table 42 which may be angularly adjusted about a vertical axis. The table 42 has a platform 50 connected thereto for relative movement toward and away from the head 12 and the platform 50 is also provided with adjustable slots 52 for supporting head and tailstocks 53 and 54 which include centers between 30 which is mounted a work gear W.

35 In the operation of the machine a work gear W is mounted between the head and tailstocks 53 and 54 in position to mesh with the lap L carried by the head 12. The platform 50 is constructed so as to have relatively slight movement toward and away from the head 12 and suitable means are provided for biasing the platform 50 toward the head 12 with a substantially constant but relatively small force. When the teeth of the gear W and the lap L have come into light pressure contact as a result of the biasing force aforesaid, the platform 50 is rigidly locked in position, after which the gear lapping operation takes place. The gear lapping operation

results from relatively rapid rotation of the gear and lap in mesh and reciprocation of the carriage 20. During this operation the table 42 is in angularly adjusted position so that the axis of the work gear W extends at an oblique angle with respect to the direction of traverse of the carriage 20. Furthermore, the head 12 is angularly adjusted so that the lap will mesh with the work gear W with the axes of the gear and lap crossed at a limited angle as between three degrees and twenty degrees.

In order to effect engagement between the teeth of the gear and lap under light but substantially constant pressure contact as aforesaid, the detailed construction illustrated in Figures 2-6 is employed. Referring first to Figure 3, the platform 50 is pivoted to the table 42 by a pivot pin 60. Adjacent the forward edge of the platform 50 are adjustable biasing springs 61, best seen in Figure 5, these springs seating at their lower end against the table 42, which as previously noted is clamped in angularly adjusted position on the rocking table 30, suitable clamping bolts being shown at 62. A cup-shape adjusting plug 63 is threaded into a threaded opening as shown. By means of the construction, a substantially constant biasing force is provided which may be adjusted so as to urge the platform upwardly so as to cause contact between the gear and lap to take place under uniform light pressure conditions, independent of the actual position of the platform when contact is established.

Means are provided for rigidly locking the platform in adjusted position. These means are for the most part located in a housing 64 doweled and bolted to the forwardly extending free edge of the platform 50. This housing includes a recess 65 (Figure 6) which receives an inverted U-shaped yoke 66 secured by bolts 67 (Figure 4) to the table 42. Beneath the yoke 66 is a hardened wear plate 68.

Extending forwardly from the platform 50 is a camming and clamping structure which is permitted limited up and down movement between the yoke 66 and plate 68.

This structure comprises an elongated threaded stud 70 rigidly and non-rotatably mounted in the forward edge of the platform 50. Rigidly seated in a recess in the forward edge of the platform 50 is a wedging element 72, which as illustrated may be held in place by stud 70. Element 72 has upper and lower inclined surfaces 73 and 74 respectively. Threaded to the stud 70 for rotation and longitudinal motion thereon is a nut 75, having pinion teeth 76, a cam 77 and a cylindrical or spherical end portion 78. A carrier plate 80, having a spherical seat therein interfitting with the spherical end portion 78 of the nut, is received between the nut 75 and wedge element 72, and is provided with an enlarged bore 81 so that it may rock on its spherical seat. Plate 80 has pairs of forwardly projecting ears 82 carrying pins 83 on which rollers 84 are mounted. The rollers 84 have substantial clearance with respect to pins 83, as illustrated, and are therefore radially movable thereon.

Cam 77, as best seen in Figure 7, has a high portion of uniform radius between radii R2, a low portion of uniform radius between radii R1, and rise and fall portions between radii R1 and R2. Bias spring 61 keeps the platform elevated to keep cam 77 in contact with the underside of yoke 66 except when the teeth of the gear and lap depress the platform. When the high por-

tion of the cam between radii R2 is in contact with the yoke, the platform is depressed to loading position.

Referring again to Figure 2, an air cylinder 90 is supported by the housing 64 and is provided with a piston connected to a piston rod 91 which is threaded or otherwise suitably secured to an actuating bar 92 which is provided with rack teeth 93 at its underside which mesh with the pinion teeth 76 formed on the nut 75.

With the cam 77 in position such that the raised portion thereof intermediate the radii R2 is in contact with the underside of the cross piece of the yoke 66, the platform 50 is in depressed or loading position. At this time a work gear W may be mounted between head and tailstocks 53, 54 and it will be in loose mesh with respect to the lap L. At this time the apparatus is in condition for initiation of an automatic cycle. This cycle comprises initially admitting motive fluid to the cylinder 90 which will cause the bar 92 to move to the right as seen in Figure 2, thereby rotating the nut 75. Initial rotation of the nut will cause corresponding rotation of the cam 77 formed thereon and will move the elevated portion of the cam between radii R2 out of engagement with the yoke 66 and will thus permit upward locking movement of the platform 50 under the biasing force supplied by the compression springs 61. Upward movement of the platform 50 continues until the teeth of the work gear W and lap L come into light pressure contact, this contact being established by the adjustment of the compression springs 61. The position of the platform 50 when its upward motion is thus arrested will depend upon the exact dimensions of the work gear and thus may vary between small limits.

It is essential in order that the subsequent lapping operation be carried out under suitable conditions for the platform to be rigidly locked in position during the traverse strokes.

Rotation of the nut 75, in addition to moving the cam 77 as just described, also advances the nut 75 to the right, as seen in Figures 3 and 6. Preferably the threads provided between the stud 70 and the nut 75 have a substantial lead so that rotation of the nut in an amount between 45 degrees and 225 degrees will effect locking of the platform. Locking of the platform is effected by causing the rollers 84 to be interposed in wedging or abutting relation between three angularly disposed surfaces. These surfaces are the upper and lower inclined surfaces 73 and 74 of the wedge member, the lower surface of the yoke 66, the upper surface of the wear plate 68, and the end surfaces of the carrier plate 80. If it so happens that the platform 50 and hence the stud 70 is in intermediate position with respect to the yoke and wear plate, the rollers 84 will enter into locking engagement as described without rocking of the carrier plate 80 on its spherical or cylindrical seat. If, however, the stud 70 and associated mechanism is closer to either the underside of the cross piece of the yoke 66 or the upper surface of the wear plate 68, full locking engagement will not take place until the carrier plate 80 has rocked on its seat 78 so as to cause the other one to move rearwardly a corresponding amount. Inasmuch as the rollers 84 are loosely mounted on their carrier pins 83 they accommodate themselves to the spaces in which they are received. Furthermore, since both of the rollers 84 are carried by a single rigid carrier plate 80, it will be apparent that when the nut 75 is advanced to the

right as seen in Figure 6 the full amount permitted before rigid engagement of the rollers 84 with the locking surfaces, a type of locking will be obtained characterized by the interposition of rigid elements between relatively movable surfaces.

Since rotation of the nut element 75 is effected by an air cylinder, forward movement of the piston in the cylinder will be arrested when the rollers 84 come into engagement with the locking surfaces. Preferably automatic controls are provided for thereafter initiating rotation of the lap and traverse of the carriage 20. The first stroke of traverse is arrested by operation of reversing switches having actuators such as 22 or 24 which initiate a return stroke of traverse. Upon completion of the return stroke of traverse, rotation of the lap and gear is stopped and the motive fluid is admitted to the cylinder so as to cause reverse movement of the piston therein. This will move the rollers 84 out of locking engagement and will also rotate the cam 77 so as to bring the elevated portion thereof into engagement with the underside of the yoke element. This has the result of moving the platform 50 downwardly so as to bring the lap and work gear into loose mesh, at which time the completed work piece may be removed. The present machine is designed to carry out a lapping operation which is characterized by its short cycle and by the fact that it is intended to remove a substantially uniform amount of material from the teeth of a series of work gears independent of small variations in size between such work gears.

As previously stated, the operation is intended to be carried out with the axis of the work gear W inclined to the direction of traverse of the carriage 20. This has two important results which make possible the present operation. In the first place, by properly selecting the angularity between the axis of the work piece and the direction of traverse, it is possible to cause the finishing action between the lap and work piece to be distributed substantially from end to end of the teeth of the lap. This has the effect of greatly increasing lap life and preventing localized wear on the lap teeth. At the same time it results in a more efficient lapping action which removes the requisite amount of material from the teeth of the gear without the necessity of repeated reciprocations, as has been required in prior lapping methods.

A third result of the use of traverse in a direction diagonal to the axis of the work gear is the gauging of the amount of material to be removed from the teeth of the work gear by the simple expedient of locating the work gear in a definite position relative to traverse when it is moved upwardly into mesh with the teeth of the lap. If the position of the work gear is such that the common normal to the axes of the lap and gear lies outside of the edges of the work gear, subsequent traverse will bring the teeth of the lap and gear into mesh at a center distance which will predetermine the amount of material to be removed from the teeth of the lap. Accordingly, the present apparatus permits a very rapid sequence of operations which will result in the removal of substantially identical amounts of material from the teeth of the work gears without requiring the careful attention of the operator. It is necessary only for the operator to remove and replace work gears between the head and tailstocks, the remainder of the operation being fully automatic.

It is particularly pointed out that the present method is not intended primarily for accurate control of final dimensions of the gear, since the final position of the work supporting platform 50 is determined by the dimensions of the gear before lapping. Prior to the present invention one of the most important uses of gear lapping was in the reclamation of rejected gears. The present method is intended as a production step in the mass production of gears and contemplates that the lapping will be applied to all gears for the purpose of improving surface finishing and effecting correction of such gear characteristics as profile, lead, concentricity, etc. Tests in production have shown that the present method improves the operating characteristics of gears by a very considerable factor and since it is possible to carry out this operation at a high production rate, it makes production lapping a practical operation in the mass production of gears.

The foregoing description has been made with particular reference to use of the machine as a gear lapping machine. However, it will be readily appreciated that the invention may be practiced when gear finishing tools of different type are employed. Thus, for example, the machine may be used with a gear shaving tool in which the teeth of the gear-like tool are provided with parallel serrations, forming adjacent cutting edges and guiding lands. The principal difference between lapping and shaving resides in the fact that the gear shaving operation is an accurate cutting operation in which a definite amount of stock may be removed in a single traverse of the gear and tool, whereas in lapping the material of the gear teeth is worn away by a rubbing action.

The machine as illustrated in Figure 1 is ordinarily provided with mechanism for effecting vertical adjustment of the knee 15 and the prior practice has been to provide a plurality of reciprocations, at the end of each of which the knee may be fed upwardly by a small predetermined amount so as to take a cut of corresponding amount on the teeth of the gear on the next stroke of traverse. The present invention may be combined with the machine including the vertical feed of the knee so as to carry out a new and improved method of finishing. Thus, for example, the gear and tool may be brought into light pressure contact as previously described, after which the first stroke of traverse may be taken. Upon completion of the first stroke of traverse and before initiation of the return stroke, the knee may be fed upwardly by a small predetermined amount. This method may if desired include additional strokes of traverse, although it is contemplated ordinarily that the gear will be completely finished in two strokes of traverse or a single back and forth reciprocation of the parts.

The machine is further capable of carrying out another modified method in which the air cylinder 90 is actuated at the end of the first stroke of traverse so that the platform 50 may move upwardly to a new position so as to remove a definite amount of stock on the return stroke. Advantage may be taken of the automatic upward movement of the platform 50 whenever the air cylinder is actuated to release the locking means to avoid the necessity of providing for automatic vertical adjustment of the knee 15. Thus, if the platform is designed to have sufficient vertical movement, a number of strokes of traverse may be taken with a corresponding re-

moval of stock upon each stroke of traverse either by shaving or lapping and the final dimension of the gear may be determined by providing an independent abutment which limits upward movement of the platform 50.

Preferably suitable means are provided for initially positioning the platform 50 in a predetermined intermediate position during setup of the machine for a run of gears. This means may constitute merely witness marks brought into registry to indicate that the platform 50 is in intermediate position. Preferably, however, it takes the form of a suitable locking means, such for example as a lug 98 projecting laterally from the yoke 66, and a hook bolt 99 mounted in the housing 64 and having a projection 100 adapted to be rotated to a position underlying lug 98, when the platform is in its depressed position. Spring pressed pin 101 is provided and is associated with recesses 102 in the bolt 99 to retain the bolt in operative or inoperative position as desired. The initial setup will then involve depressing platform 50, rotating bolt 99 to bring projection 100 beneath lug 98, releasing platform 50 to permit it to rise to the intermediate position determined by engagement between lug 98 and projection 100, loading a work gear between the stops 53 and 54, and vertical adjustment of the knee 15 to bring the gear and tool into mesh and preferably into light contact. Thereafter if an oversize gear is inserted the platform 50 may be depressed to a position below the initial set position as determined by the locating means, and if an undersize gear is present the platform will come to rest in a position above the position determined by the locating means. If a carefully checked or master gear is used in the initial setup it will insure that the average position of the platform during the first shaving stroke of traverse will be the predetermined intermediate position as set by the locating means. The upper surface of projection 100 may if desired be an inclined camming surface so that different rotational position of bolt 99 will predetermine different positions in which platform 50 is locked during initial setup.

The drawings and the foregoing specification constitute a description of the improved method of finishing gears in such full, clear, concise and exact terms as to enable any person skilled in the art to practice the invention, the scope of which is indicated by the appended claims.

What I claim as my invention is:

1. The method of finishing lapping a series of gears which comprises sequentially meshing the gears at crossed axes with a gear-like lapping tool under a relatively small, uniform pressure, with the common normal to the axes of gears and tool spaced outwardly beyond the ends of the gears more closely adjacent to said common normal to thereby determine the amount of stock to be removed from the gears, locking the gears and lap in the position of radial spacing determined by their meshed engagement without reference to the theoretical dimensions of the gears, and effecting relative traverse between the gears and lap in a direction to distribute the lapping action longitudinally of the gear teeth while rotating the gear and lap.

2. The method as defined in claim 1 in which the relative direction of traverse is diagonal to the axes of both lap and gears.

3. The method of finishing a gear which comprises initially meshing a gear member with a gear-like tool member with the axes of said members crossed at an angle of less than 30 degrees and with the common normal to the axes of said members lying a predetermined distance beyond the side of one of said members, thereafter effecting a relative radial movement between said members to bring the teeth of said members into contact with a predetermined relatively light pressure, thereafter effecting rigid locking of the members to maintain the spacing between the axes thereof, and rotating said members and effecting relative traverse between said members in a direction to cause the common normal to the axes of said members to pass from one side of said gear member to the other side thereof.

4. The method of finishing gears as defined in claim 3 in which the relative traverse between the gear and tool members is continued until the common normal to the axes of said members lies a predetermined distance beyond the other side of said one member, thereafter unlocking said members and effecting relative radial feed between said members to bring the teeth of said members into contact with the same predetermined relatively light pressure, thereafter effecting rigid locking of the members to maintain the spacing between the axes thereof, and finally effecting a reverse stroke of traverse.

5. The method of finishing gears as defined in claim 3 in which the relative traverse between the gear and tool members is interrupted when the common normal to the axes of said members is located a predetermined distance beyond one side of said one member, thereafter arresting said relative traverse, unlocking said members, effecting a relative radial feed between said members to bring the teeth of said members into contact with the same predetermined relatively light pressure, thereafter effecting rigid locking of the members to maintain the spacing between the axes thereof, and finally effecting further relative traverse between said members.

6. The method of lapping a gear which comprises supporting the gear for rotation on a vertically movable support, counterbalancing the weight of the support with a uniform force providing a relatively small substantially constant force effective to raise said support, limiting upward movement of said support by engagement between a gear on said support and a stationary gear-like lap, locking said support in the position determined by meshing engagement between the gear and lap, and thereafter rotating and traversing said gear and lap in mesh.
